UNITED STATES PATENT OFFICE.

HAMPTON R. CAMPFIELD, OF SUSQUEHANNA DEPOT, PENNSYLVANIA.

SPARK-ARRESTER.

SPECIFICATION forming part of Letters Patent No. 228,442, dated June 8, 1880.

Application filed December 31, 1879.

To all whom it may concern:

Be it known that I, HAMPTON R. CAMPFIELD, of Susquehanna Depot, in the county of Susquehanna and State of Pennsylvania, have invented a new and useful Improvement 5 in Spark-Arresters, of which the following is a specification.

The object of my invention is to provide a simpler and more effective device, and less obtrusive to the exhaust than those heretofore contrived, for preventing coal-dust and sparks carried by the draft through smoke-stacks of locomotives from annoying the passengers of a train, soiling their clothes, and from causing 15 damage by setting fire to woods and prairies adjacent to the railways.

The invention consists in the combination of a smoke-stack having a closed bottom provided with a central opening, and an interior 20 tube of wire-cloth or perforated metal plate reaching from the said opening in the bottom to the top of the stack, where it is tapered, and ends with a solid tube bent downward over the edge of the stack, as will be herein- 25 after described.

In the accompanying drawings, Figure 1 represents a side elevation of a locomotive-boiler provided with my invention. Fig. 2 is a vertical central section of the smoke-stack.

Similar letters of reference indicate like parts.

A is the boiler; a, boiler-tubes; B, boiler-furnace; C, the smoke-box; D, steam-cylinder; E, steam-exhaust nozzle from cylinder 35 D; F, the smoke-stack or chimney.

The lower end of the smoke-stack F is closed at its junction with the smoke-box C, except a central opening, H, in the bottom, perpendicularly above the nozzle E, said opening being bordered on the upper side of the bottom 40 by a vertical nipple, H', in which are formed one or more openings, h, whose lower edges are flush with the bottom of the stack. Upon and surrounding the outer surface of the said 45 nipple, above its side openings, h, is fitted a vertical tube, G, of wire-cloth or perforated metal plate, reaching up to within a short dis-

tance of the top of the stack, and tapering, by a cone, g, of not perforated plate, into a pipe, I, which is curved downward over the 50 edge of the stack toward the track, or connected with the fire-box B, as usual.

By this construction the natural draft, proportioned to the height of the stack F, increased by the heat and velocity of the exhaust-steam from the nozzle E, causes the smoke and gases of combustion to always pass through the perforated tube G before escaping through the top of the stack F, and the sparks and coal-dust, retarded by striking against the 60 sides of the tube G, fall and whirl about in the tube until discharged by the central draft into and through the pipe I to the ground or to the boiler-furnace B.

Minute particles which may have passed 65 through the meshes of the tube G and fallen into the surrounding space in the stack F will gradually drop through the openings h into the smoke-box C, whence, if not carried off through the pipe I by the steam-draft from the nozzle 70 E, they may be readily removed.

In United States Patent No. 166,040, to which I refer as the nearest sample of the state of the art previous to this my invention, too much obstruction is interposed to the exhaust 75 for carrying the sparks to the pipe I and the furnace, and too little obstruction for preventing them from passing out through the stack in the usual primitive way, thus making that device inoperative for its purpose.

Having thus described my invention, I claim as new and desire to secure by Letters Patent—

The combination, with a smoke-stack, F, provided with a central opening, H, in its bottom, of the interior perforated tube, G, with or without the nipple H', and the exterior discharge-pipe, I, forming an extension of said tube, substantially as described.

HAMPTON R. CAMPFIELD.
